US00D905666S

(12) **United States Design Patent** (10) **Patent No.:** **US D905,666 S**
(45) **Date of Patent:** **** Dec. 22, 2020**

(54) **EARHOOK FOR EARPieces**

(71) Applicant: **SPiGEN KOREA CO., LTD.**, Seoul (KR)

(72) Inventor: **Sun Woo Yun**, Seoul (KR)

(73) Assignee: **SPiGEN KOREA CO., LTD.**, Seoul (KR)

(**) Term: **15 Years**

(21) Appl. No.: **29/715,629**

(22) Filed: **Dec. 3, 2019**

Related U.S. Application Data

(63) Continuation of application No. 29/603,761, filed on May 12, 2017, now Pat. No. Des. 870,079.

(57) **CLAIM**

The ornamental design for an earhook for earpieces, as shown and described.

DESCRIPTION

FIG. 1 is a front elevational view of an earhook for earpieces;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view of the earhook assembled to an earpiece;

FIG. 8 is a front perspective view of the earhook separated from the earpiece;

FIG. 9 is a rear perspective view of the earhook to the earpiece; and,

FIG. 10 is a rear perspective view of the earhook separated from the earpiece.

In the drawing, the claimed design is defined by the shaded surfaces; the broken lines depict environment that forms no part of the claimed design.

1 Claim, 10 Drawing Sheets
